(57) **CLAIM**

The ornamental design for an earbud case holder with three charger cutouts, as shown and described.

DESCRIPTION

FIG. 1 is a perspective view of an earbud case holder with three charger cutouts, showing our new design;

FIG. 2 is another perspective view thereof;

FIG. 3 is a front view of the earbud case holder with three charger cutouts, shown in an alternate configuration in a closed position;

FIG. 4 is a rear view thereof;

FIG. 5 is a left view thereof, wherein a first charger cutout is depicted;

FIG. 6 is a right view thereof, wherein a second charger cutout is depicted;

FIG. 7 is a top view thereof;

FIG. 8 is a bottom view thereof, wherein a third charger cutout is depicted; and,

FIG. 9 is another perspective view of the earbud case holder with three charger cutouts of FIG. 1.

The broken line in the figures represent stitching and portions of the earbud case holder with three charger cutouts that form no part of the claimed design. The dash-dot-dash lines in the figures represent environmental structure and form no part of the claimed design.
